UNITED STATES PATENT OFFICE.

HENRY ADLER, OF PITTSBURG, PENNSYLVANIA.

STOVE.

SPECIFICATION forming part of Letters Patent No. 600,702, dated March 15, 1898.

Application filed January 6, 1897. Serial No. 618,140. (No model.)

To all whom it may concern:

Be it known that I, HENRY ADLER, a citizen of the United States, residing at Pittsburg, in the county of Allegheny and State of Pennsylvania, have invented certain new and useful Improvements in Stoves; and I do hereby declare the following to be a full, clear, and exact description thereof.

My invention relates to gas-stoves, and has special reference to stoves for burning natural or other gaseous fuel.

The object of my invention is to provide a gas-stove which is neat in appearance and can be easily and cheaply constructed.

Another object of my invention is to provide a gas-stove of light material which can be quickly and conveniently put together and taken apart when desired, and a still further object of my invention is to provide such a stove in which proper and complete combustion can be obtained by the admission of air and gas thereto, so as to attain as great a heating power as possible and overcome the admission of gaseous vapors into the apartment in which it is used as well as the production of a most powerful radiant heat, at the same time the utilization of as much of the waste heat as possible before it passes away up the flue.

My invention consists, generally stated, in the novel construction, arrangement, and combination of parts, as hereinafter more specifically set forth and described, and particularly pointed out in the claims.

To enable others skilled in the art to which my invention appertains to construct and use the same, I will describe the same more fully, referring to the accompanying drawings, in which—

Figure 1 is a front or face view of my improved gas-stove. Fig. 2 is an end view of the same. Fig. 3 is a vertical central section thereof on the line 3 3, Fig. 1. Fig. 4 is a back view of the same. Fig. 5 is a top view of the same with the cover removed. Fig. 6 is a horizontal cross-section on the line 6 6, Fig. 1, looking down in the direction of the arrow. Figs. 7, 8, and 9 are enlarged detail sections of different parts of the stove. Fig. 10 is a plan view of the blank for forming the back, sides, and front of the stove. Fig. 11 is a plan view of the blank for forming the

top or cover of the stove, and Fig. 12 is a like view of the blank for forming the brace or base of the stove.

Like letters herein indicate like parts in each of the figures of the drawings.

My improved gas-stove A is formed from sheet metal and is provided with the front panels *a a*, ends *b b*, and back *c*, which are formed from one piece of sheet metal and bent to shape, as shown. The back *c* has a flange *c'* on the bottom thereof, bent inwardly to assist in supporting the stove A, and air-entrance openings *c''* are formed in the back *c* for the entrance of air into the air-chamber *d*, formed in the stove A. Air-entrance openings *b'* are also formed in the ends *b b* on each side of the stove A for the entrance of air into the heating-chamber *d* therein.

Secured within the chamber *d* of the stove A is the corrugated metal back wall *e*, which has a number of perforations *e'* therein and is secured to the ends *b b* by bolts *e''*, passing through flanges *e'''* bent thereon. The corrugated metal back *e* does not extend down to the bottom of the stove A, thus leaving a space *e''* for the proper circulation of air in the heating-chamber *d*. The corrugated back wall *e* has the upwardly-inclined hood *f*, bent inwardly toward the front of the stove A at its top over the combustion-chamber *g*, for inducing the products of combustion to follow the circuitous route before reaching the off-take-flue.

Secured to the corrugated back *e* and extending over the combustion-chamber *g* above the hood *f* is the top *h*, which is also secured to the ends *b b* by bolts *h'*, extending through the flanges *h''* thereof. A pipe *i* leads off from the top *h* above the hood *f* into and through the collar *i'*, secured by bolts *i''* on the back *c*, with which pipe *i* and collar *i'* any suitable connection can be made to a flue for carrying off the waste gases. A downwardly-projecting flange *h'''* is formed on the front of the top *h*, which fits under and against the downwardly-projecting flange *j'* on the cover *j*, so as to form a space *j''* between the same in which any suitable non-conducting material can be placed—such as asbestos, mineral wool, &c.—to prevent the heat from marring the appearance of the cover *j*. The cover *j* extends over the front panels *a a*, ends *b b*,

and back *c* of the stove *A*, and is secured thereto by the lip *j*³, formed thereon, engaging with a lip *c*³, formed on the back *c*. The cover *j* is provided with flanges *j*⁴ on each side, which fit over the ends *b b* and hold the cover *j* in place in conjunction with the lip *j*³ and the bolts *j*⁵, which pass through the downwardly-projecting flange *j*⁴ and panels *a a* of the stove *A*. A series of openings *j*⁶ are formed 5 in the cover *j* above the top *h* for the passage of heated air into the apartment from the stove *A*. Asbestos fiber *k* or other suitable non-conducting material is placed on the front of the corrugated back *e* and around 10 the ends *b b*, and a series of metal branches *l* are placed in front of the corrugated back *e* and fiber *k*, which are adapted to slide on rods *l*', secured in the ends *b b* of the stove *A* by means of collars *l*² on the branches *l* fitting 15 around the rods *l*', these metal branches *l* serving to diffuse and spread the products of combustion from the asbestos *k*, which is affixed to the back wall *e*. Nuts *l*³ engage with the ends of the rods *l*' to hold them in place 20 in the ends *b b* of the stove *A*.

The burner *m* is secured in the ends *b b* of the stove *A*, below the branches *l*, by means of bolts and nuts *m*', said burner being preferably of the construction shown and described in the Letters Patent granted to me 25 on November 1, 1892, No. 485,594, and on May 19, 1896, No. 560,458. A gas-supply pipe *n* enters one of the air-openings *b*' in one of the ends *b b* and connects with the burner 30 *m* for supplying gaseous fuel to the stove *A*. A brace or base *o* is secured to the panels *a a* on the stove *A* by means of bolts *o*' passing through holes *o*² in the same and through a support *o*³, which is secured to a flange *o*⁴ on 35 the brace *o*, which acts to support the stove *A*. The brace *o* is provided with open ends *o*⁵ and air-openings *o*⁶ in the body of the same for the entrance of air into the burner *m* and chamber *d*. The top *o*⁷ of the brace *o* is bent 40 to form the seat *o*⁸ for the reception of the front or fender *p*, which is held therein by means of the flange *o*⁹ and rests against the burner *m*. The front *p* is provided with the bearing *p*', within which any suitable handle 45 or ring *p*² is secured for handling the front or fender *p*.

The blank *q* for making the front panels *a a*, ends *b b*, and back *c* of my improved stove *A* is shown in Fig. 10 and is stamped 55 out of sheet metal in any suitable manner to form the body portion *q*' for the back *c* and the wings *q*² for forming the ends *b b* and the front panels *a a* of the stove. The blank is provided with air-openings *b*' and *c*' therein 60 and the flanges *c*' *c*³ for supporting the stove and forming the lip for the cover *j*. An opening *r* is formed in the blank *q* for the pipe *i*, and holes *r*' are formed around the same for the bolts *i*², holding the collar *i*' to the back *c*. Holes *s* are formed in each panel *a a* for 65 the bolts *j*⁵ to hold the cover *j* thereto, and holes *t* are also formed in the panels *a a* for

the bolts *o*', which secure the brace *o* and support *o*² thereto. Holes *u* are also formed in the upper part of the blank *q* for the bolts *h*', which hold the top *h* thereto, and holes *v* are formed in the blank *q* for the bolts *e*² for supporting the corrugated back *e* within the stove *A*. Holes *v*' in the blank *q* are adapted to seat the bolts *m*', which secure the burner *m* within the stove *A*, and the holes *v*² are adapted to support the rods *l*', with which the branches *l* engage. 70

The blank *w*, stamped from metal, for forming the cover *j* is shown in Fig. 11 and has 80 the body portion *w*' and the flange portion *w*² for forming the depending flange *j*⁵ and also the lip *j*³ and the flanges *j*⁴ thereon. Holes *j*⁶ are formed in the flange portion *w*² for the reception of the bolts *j*⁵. 85

In Fig. 12 is shown the blank *c*, which is stamped from sheet metal, for forming the brace or base *o* of the stove, and it is provided with the body portion *z*⁵ and the wing portion *z*² thereon for forming the seat *o* *h* for 90 the fender. Holes *o*² are formed in the body portion *z*' for the reception of the bolts *o* to secure the brace to the panels *a a* of the stove *A*.

The manner of constructing and operating 95 my improved gas-stove is as follows: The blank *q* after it is stamped, as shown in Fig. 10, is bent to shape to form the front panels *a a*, ends *b b*, and back *c*, after which the corrugated back *e*, with its hood *f*, top *h*, and pipe *i* connected thereto, is then set in place and secured by the bolts *e*² and *h*' to the ends *b b*. After the fiber *k* has been placed upon the corrugated back *e* and ends *b b* the rods *l*' are set in place with the branches *l* thereon 100 and the rods secured in the ends *b b* by the nuts *l*³ engaging therewith. The burner *m* can then be set in place by means of the bolts *m*', engaging with the ends *b b*, and the gas-supply pipe *n*, connected thereto, through 105 the air-openings *b*' in one of the ends *b b*. The brace *o*, which has previously been stamped and bent to shape from the blank *z*, is then secured to the panels *a a* by means of the bolts *o*' and support *o*² and the front *p*, 110 placed within its seat *o*⁷ and against the burner *m*. The cover *j*, which has been bent from the blank *w*, can then be slid to place by means of the lip *j*³, engaging with the lip *c*³ on the back *c* and secured to the front 115 panels *a a* by the bolts *j*⁵, engaging with the downwardly-projecting flange *j*⁴ thereon and the asbestos fiber or other non-conducting material placed within the space *j*² between the flange-openings *j*⁶ in the cover *j* into the 120 apartment, and the air to the burner *m* will be drawn into the stove *A* through the openings *b*' in the ends *b b* and the air-openings *o*⁵ and open ends *o*⁴ in the brace *o*, so giving 125 a sufficient amount of air to form perfect combustion in the burner *m* and a sufficient quantity of air to be heated in the heating-chamber *d* before passing into the apartment. It will thus be seen that my improved 130

stove is neat and simple in its construction and strong and durable in its parts. By such a construction it can be easily and cheaply manufactured and will lessen the number of 5 pieces and parts composing the same, so reducing the handling and working of the same. By its construction greater heat is obtained than in the ordinary gas-stove and no heat whatever is lost by its use. The whole of the 10 products of combustion passes away by the flue, while pure air admitted at the bottom of the stove is warmed in the chamber and passes into the apartment through the perforated top panels without ever coming in contact 15 in any way with the burned gases.

What I claim as my invention, and desire to secure by Letters Patent, is—

1. A gas-stove formed from a blank of sheet metal having a body portion for forming the 20 back thereof, wings on said body portion for forming the ends and front panels of the stove, and a cover or top formed from a blank of sheet metal having a body portion provided with a wing portion thereon for forming a depending 25 flange for the front of the stove, substantially as and for the purposes set forth.

2. A gas-stove formed from a blank of sheet metal having a body portion for forming the back thereof, wings on said body portion for 30 forming the ends and front panels of the stove, and a front brace or base formed from a blank of sheet metal having a body portion and a wing portion for forming a seat for the reception 35 of a front or fender, substantially as and for the purposes set forth.

3. A gas-stove formed from a blank of sheet metal having a body portion for forming the back thereof, wings on said body portion for forming the ends and front panels of the stove, 40 a cover or top formed from a blank of sheet metal having a body portion provided with a flange portion thereon for forming a depending flange for the front of the stove, and a front brace or base formed from a blank of 45 sheet metal having a body portion and a wing portion for forming a seat for the reception of a front or fender, substantially as and for the purposes set forth.

4. A gas-stove provided with a heating- 50 chamber and means for supplying air thereto, a combustion-chamber in front of the heating-chamber, a top extending over the combustion-chamber and provided with a depending flange, and a perforated cover or top extending over the heating and combustion 55 chambers and provided with a downwardly-projecting front or flange, substantially as and for the purposes set forth.

5. A gas-stove provided with a heating- 60 chamber and means for supplying air thereto,

a combustion-chamber in front of the heating-chamber, a top extending over the combustion-chamber and provided with a depending flange, a perforated cover or top extending over the heating and combustion chambers 65 and provided with a downwardly-projecting front or flange, and non-conducting material between the depending flange of the top and the downwardly-projecting flange on the cover or top, substantially as and for the purposes 70 set forth.

6. A gas-stove provided with a heating-chamber and means for supplying air thereto, a combustion-chamber in front of the heating-chamber, a top extending over the combustion-chamber and provided with a depending flange, a perforated cover or top having a downwardly-projecting front or flange extending over the heating and combustion chambers, and a hood within the said combustion-chamber below the top and extending into proximity to the depending flange thereof, substantially as and for the purposes set forth. 75

7. A gas-stove provided with a heating-chamber and means for supplying air thereto, 85 a combustion-chamber in front of the heating-chamber, a top extending over the combustion-chamber and provided with a depending flange, a perforated cover or top having a downwardly-projecting front or flange extending over the heating and combustion chambers, a hood within said combustion-chamber below the top and extending into proximity 90 to the depending flange thereto, and a space between said hood and top of the combustion-chamber for the passage of the products of combustion to the flue, substantially as and for the purposes set forth. 95

8. A gas-stove having a burner therein, and movable metal branches within the stove 100 above the burner, substantially as and for the purposes set forth.

9. A gas-stove having a burner therein, and movable metal branches within the stove 105 above the burner, said branches being adapted to slide on rods secured within the stove, substantially as and for the purposes set forth.

10. A gas-stove having a burner therein, and a front brace or base secured to said stove having a seat therein for the reception of a 110 front or fender and provided with open ends for the admission of air to the burner, substantially as and for the purposes set forth.

In testimony whereof I, the said HENRY ADLER, have hereunto set my hand.

HENRY ADLER.
